UNITED STATES PATENT OFFICE.

FRANK J. GLANVILLE, OF MORRISTOWN, NEW JERSEY.

ELASTIC HORSESHOE-CALK.

1,177,099.

Specification of Letters Patent. Patented Mar. 28, 1916.

Application filed February 11, 1916. Serial No. 77,581.

To all whom it may concern:

Be it known that I, FRANK J. GLANVILLE, a citizen of the United States, and a resident of the city of Morristown, in the county of 5 Morris, State of New Jersey, have invented certain new and useful Improvements in Elastic Horseshoe-Calks, of which the following is a specification.

The invention relates to devices adapted 10 to be attached to horse shoes for the purpose of providing an elastic and non-slip tread.

It has for its objects, among others, the provision of a tread of this character of simple, strong and durable character and in- 15 expensive construction, which may be quickly attached to or detached from the shoe, but will remain attached thereto under all the ordinary conditions and strains of use.

20 To these ends the invention consists in the construction and arrangement of parts hereinafter described and claimed, and illustrated in the accompanying drawings.

In the said drawings, Figure 1 is a plan 25 of a shoe and calk embodying the improvements; Fig. 2 is a side elevation; Fig. 3 is a bottom view; Fig. 4 is a vertical cross-section on the line 4—4 of Fig. 1; Fig. 5 is a similar section on the line 5—5 of Fig. 2, 30 and Fig. 6 is an enlarged perspective of the connecting member between the elastic tread and the shoe.

The shoe A is of the usual form and is 35 provided with four holes A' for receiving the expandable sleeves B of the connecting member. These holes are shown as of the same diameter throughout, but may be made of varying diameter if desired. The central bore B' of the sleeve is also of the same 40 diameter throughout, but may be made of inwardly decreasing diameter if desired, so as to give more expansion.

The plate B² is preferably integral with 45 the sleeve B and has a downwardly extending portion B³ with an opening B⁴ through which a rivet C or other suitable connecting member passes in order to secure to it the elastic tread D. The said tread is provided with apertures D' running through it and 50 adapted to be alined with the central bore of the sleeve B and the opening in the plate B² so that a small spike E may be passed therethrough and driven into the sleeve. The outer surface of the tread is provided 55 with corrugations D². It is also preferably provided with reinforcing wires D³ run-

ning through it lengthwise near the bottom and beneath the rivets C. These wires not only reinforce the tread but tend to make the hold of the rivets more secure.

The calk is secured to the shoe by placing the expandable sleeves B in the apertures A' of the shoe and then driving the nails E into the said sleeve and expanding them. This forms a secure connection which will 60 resist all the stress of use. When it is desired to remove the calk it is only necessary to drive the edge of an instrument, such as a chisel, in between the bottom surface of the shoe and the plate B² and then pry the plate 65 and the parts connected therewith loose. It will be observed that the shock caused by contact between the tread and the road surface will have a tendency to drive the nail E inward and thus make the connection more 70 secure, instead of weakening it, and also when the elastic tread wears down in use it will be reinforced by this nail and also by the part B³. In this manner an elastic tread 75 extending around the shoe with a metal reinforcement is provided, which will hold its position and maintain its efficiency until 80 completely worn down, and which at the same time may be quickly removed and replaced when necessary. The shoe is also so 85 constructed that it may be worn if desired without the calk and will be as serviceable and as durable as the ordinary shoe.

The details of construction herein de- 90 scribed and shown may be varied within cer- 95 tain limits without departing from the scope of the invention, and it is not the intention to limit the claims to such details of construction except so far as they may be there- in set forth.

What I claim is:

1. A device of the character described, comprising a compressible tread, a shoe pro- 100 vided with apertures, metallic connecting members, means for securing the tread thereto, expandible members adapted to be placed in said apertures, and means for expanding the same therein.

2. A device of the character described, comprising a compressible tread, a shoe pro- 105 vided with apertures, metallic connecting members, means for securing the tread thereto, expandible members adapted to be placed in said apertures, and an expanding device adapted to be passed through the tread and 110 driven into the said expandible members to expand the same.

3. A device of the character described, comprising a compressible tread, a shoe provided with recesses therein, metallic connecting members, means for securing the tread thereto, expandible members adapted to be placed in said apertures, and removable means for expanding the same therein. 5
4. A device of the character described, comprising a compressible tread, a shoe provided with recesses therein, metallic connecting members, means for securing the tread thereto, an expandible sleeve adapted to be placed in said apertures, and removable means for expanding the same therein. 10
- 15 5. A device of the character described, comprising a compressible tread, a shoe provided with recesses therein, metallic connecting members, means for securing the tread thereto, hollow expandible members adapted to be placed in said apertures, and an expanding device adapted to be passed through the tread and driven into the said expandible members to expand the same. 20
6. The combination of a metallic shoe, provided with recesses therein, metallic connecting members having portions extending into said recesses, a flexible calk extending over the bottom of the shoe and connected with and also forming a connection between the said members, and means for expanding the portion of the connecting members within the recess. 25
- 30

Witness my hand this 7th day of February 1916, at the city of New York, in the county and State of New York.

FRANK J. GLANVILLE.
